US0D1043967S

(12) **United States Design Patent** (10) **Patent No.:** **US D1,043,967 S**
(45) **Date of Patent:** **** Sep. 24, 2024**

(54) **INJECTION DEVICE**

(71) Applicant: **Sanofi**, Paris (FR)

(72) Inventors: **Christian Rogge**, Munich (DE);
Philipp Oster, Munich (DE); **Carolin Frontzek**, Munich (DE); **James Collins**, Bridgewater, NJ (US); **Alex Zuyev**, Frankfurt am Main (DE); **Kai Scheinert**, Frankfurt am Main (DE);
Uwe Dasbach, Frankfurt am Main (DE); **Marc Schader**, Frankfurt am Main (DE)

(73) Assignee: **Sanofi**, Paris (FR)

(**) Term: **15 Years**

(21) Appl. No.: **29/764,089**

(22) Filed: **Dec. 28, 2020**

Related U.S. Application Data

(62) Division of application No. 29/648,590, filed on May 22, 2018, now Pat. No. Des. 908,868.

(57) **CLAIM**

The ornamental design for injection device, as shown and described.

DESCRIPTION

FIG. 1 is a perspective view of a first embodiment of the injection device with cap showing our new design;

FIG. 2 is a front view thereof;

FIG. 3 is a back view thereof;

FIG. 4 is a first side view thereof;

FIG. 5 is a second side view thereof;

FIG. 6 is a top view thereof; and

FIG. 7 is a bottom view thereof.

FIG. 8 is a perspective view of a second embodiment of the injection device with cap showing our new design;

FIG. 9 is a front view thereof;

FIG. 10 is a back view thereof;

FIG. 11 is a first side view thereof;

FIG. 12 is a second side view thereof;

FIG. 13 is a top view thereof; and,

FIG. 14 is a bottom view thereof.

The broken lines in the drawings depict portions of the injection device that form no part of the claimed design.

1 Claim, 8 Drawing Sheets
